W. C. CARTER.
INTERNAL COMBUSTION ENGINE.
APPLICATION FILED AUG. 17, 1911.

1,081,432.

Patented Dec. 16, 1913.

UNITED STATES PATENT OFFICE.

WILLIAM C. CARTER, OF ST. LOUIS, MISSOURI, ASSIGNOR TO CARTER CARBURETOR COMPANY, OF ST. LOUIS, MISSOURI, A CORPORATION OF MISSOURI.

INTERNAL-COMBUSTION ENGINE.

1,081,432.

Specification of Letters Patent. Patented Dec. 16, 1913.

Application filed August 17, 1911. Serial No. 644,532.

To all whom it may concern:

Be it known that I, WILLIAM C. CARTER, a citizen of the United States, residing at St. Louis, Missouri, have invented a certain 5 new and useful Improvement in Internal-Combustion Engines, of which the following is a full, clear, and exact description, such as will enable others skilled in the art to which it appertains to make and use the 10 same.

This invention relates to internal combustion engines.

The main object of my invention is to provide an internal combustion engine 15 which has not the objectionable features of internal combustion engines of the type in which puppet valves are used for controlling the admission and exhaust of the gases.

Another object is to provide a noiseless, 20 smooth running engine which has greater power than the internal combustion engines now in general use.

Another object is to provide an engine which is so designed that carbon cannot be- 25 come deposited on the valves and valve seats, thereby overcoming the necessity of continually regrinding the valves as is necessary with the engines now in general use. And still another object is to provide an 30 inexpensive engine of simple construction which is so designed that the cylinders can be cleaned easily and without taking down the engine.

Other objects and desirable features of 35 my invention will be hereinafter pointed out.

Broadly stated, my invention consists in an internal combustion engine having an admission port and an exhaust port prefer- 40 ably formed in the sides of each of its cylinders, and one or a plurality of recipro- cating slide valves arranged inside of each cylinder for controlling the admission and exhaust of the gases through said ports. I 45 prefer to use a single valve for controlling both of said ports and form said valve from a split expansion ring of practically the same design as the split expansion rings which are now generally used on the pistons 50 of internal combustion engines but I do not wish it to be understood that my invention is limited to an engine provided with such a means for controlling the admission and exhaust of the gases. Instead of casting the 55 end of the cylinder integral with the side walls I prefer to use a piston to form the

end of the cylinder and mount the slide valve on said piston. Any suitable means may be employed for actuating the piston head of the cylinder so as to cover and uncover the ports which the slide valve on the piston head controls but I prefer to use cams for this purpose which are so designed and arranged that they roll upon instead of strike against the member or members which 60 they move.

Figure 1 of the drawings is a vertical transverse sectional view of an internal combustion engine constructed in accordance with my invention; Fig. 2 is a vertical sec- 70 tional view taken on the line 2-2 of Fig. 1; Fig. 3 is a detail vertical sectional view, showing the slide valve arranged in such a position that the burnt gases can escape through the exhaust port; and Fig. 4 is a 75 similar view showing said valve arranged in such a position that the combustible gases can pass through the admission port into the cylinder.

Referring to the drawings which illustrate 80 the preferred form of my invention, A designates one cylinder of the engine which is preferably provided with a water-jacket 1. The piston 2 may be of any preferred type and may be connected to the crank 85 shaft of the engine in any suitable manner. The closed end of the cylinder A is preferably formed by a piston 3 provided with piston rings 4 or other suitable means for insuring a tight joint between the ex- 90 terior of same and the inner surface of the side walls of the cylinder, and the sides of the cylinder have an admission port 5 and an exhaust port 6 formed therein. The ports 5 and 6 preferably consist of horizon- 95 tally disposed segmental-shaped slots ar- ranged in different horizontal planes, as shown in broken lines in Fig. 1, the admis- sion port 5 being located a trifle higher up than the exhaust port 6 of the engine herein 100 shown.

A reciprocating slide valve B which pref- erably consists of a split expansion ring, is carried by a spider formed from a plurality of wings 7 on the lower end of the piston 105 head 3 and a ring-shaped member 7^a which surrounds said wings and is connected to same. Said valve B is wide enough to cover both of the ports 5 and 6 when it is in a certain position, and the ports 5 and 6 are 110 so arranged with relation to each other that the port 5 will be closed and the port 6 open

when the valve B is in another position and the port 5 will be open and the port 6 closed when the valve B is in still another position. The valve B is arranged far enough below the bottom of the piston head 3 to permit the 5 gases to flow into the cylinder over the upper edge of the valve B when the admission port 5 is open, and any suitable means may be employed for holding the valve B in position with relation to the spider on the lower end of the piston head 3, such, for example, as an annular rib 8 on the inner side of the valve that fits in an annular recess formed in the outer face of the ring-shaped member 7^a of the spider and a pin 10 or other suitable device (not shown) on the spider for preventing the valve from rotating.

The means which I prefer to use for reciprocating the piston head 3 consists of a 20 cam shaft 9 provided with a pair of cams 10 which engage the top face of the piston head 3 and move it downwardly, and a cam 11 arranged between the cams 10 and cooperating with a cross-head 12 on the piston head 3 to move said piston head upwardly. The cross-head 12 is mounted on vertically disposed pins or uprights 13 on the piston head 3, and if desired coiled compression springs 25 14 may be arranged between said cross-head and nuts 15 on the upper ends of the uprights 13 so as to permit said cross-head to yield and thus prevent breakage in case an obstruction gets between the cams and the 30 top face of the piston head 3 on which the cams bear. The cams 10 are preferably so designed that they roll upon the top face of the piston head 3, and the cam 11 is so designed that it rolls upon the cross-head 12, 35 thus producing practically a noiseless operating mechanism for the piston head. The top face of the piston head 3 is provided with a recess 16 so as to form a clearance for the intermediate cam 11 and thus permit the 40 piston head to move upwardly when the high point of said cam 11 strikes against the lug 12^a on the under side of the cross-head 12. The cams 10 and 11 are so arranged and timed that the valve B will cover 45 the admission port 5 and the exhaust port 6 when the piston 2 is moving upwardly on its compression stroke and downwardly on its power stroke, the piston head 3 being held at rest during this period of the cycle 50 55 of operations of the engine by means of the cams 10 which bear upon the top face of the piston head 3 and the cam 11 which bears against the under side of the cross-head. Any suitable means such, for example, as a 60 spark plug S may be used for igniting the charge. When the piston 2 starts to move upwardly so as to expel the burnt gases from the cylinder the high point of the cam 11 engages the lug 12^a on the under side of the 65 cross-head 12 and thus moves the piston

head 3 upwardly, as shown in Fig. 3, the recess 16 in the top face of said piston head providing sufficient clearance for the cam 11 to permit the piston head 3 to move upwardly far enough to cause the exhaust port 70 6 to be uncovered without uncovering the admission port 5, and thus permitting the burnt gases to escape through the exhaust port 6 into the exhaust manifold 18. After the cylinder has been scavenged in this manner the piston head 3 is moved downwardly 75 by the cams 10 far enough to uncover the admission port 5 without uncovering the exhaust port 6, as shown in Fig. 4. The combustible gases are drawn into the cylinder 80 A over the upper edge of the valve B on the downward stroke of the piston 2, as shown in Fig. 4, and after the charge has been drawn into the cylinder in this manner the piston head 3 is returned to the position 85 shown in Fig. 1 by means of the cam 11 whose surface *x* acts upon the lug 12^a on the under side of the cross-head 12 on the piston head, said piston head being held at rest in the position shown in Fig. 1 during the succeeding compression stroke and power stroke 90 of the piston 2.

An engine of the construction above described operates noiselessly and smoothly owing to the fact that the valve B which 95 controls the admission and exhaust of the gases reciprocates back and forth in the cylinder without striking against a valve seat or other metallic part, and the cams 10 and 11, which impart movement to said 100 valve, roll upon the top face of the piston head and the cross-head 12 connected thereto, the engine being so designed that the cams 10 always remain in engagement with the piston head 3 and the cam 11 always remains 105 in engagement with the lug 12^a on the under side of the cross-head 12 that is connected to the piston head. There is no chance for carbon to become deposited on the inner wall of the cylinder adjacent the admission 110 and exhaust ports owing to the fact that the valve B covers both of said ports and thus snugly engages the portion of the sides of the cylinder adjacent thereto when the charge is fired. Another advantage of such 115 a construction is that the valve B is always properly lubricated because said valve occupies such a position when the charge is ignited that the explosion cannot burn off the oil on the side walls of the cylinder against 120 which the valve B bears. There is little chance for the gases to escape from the cylinder of such an engine because the valve which controls the admission and exhaust of the gases consists of a split expansion 125 ring which always remains pressed tightly against the inner wall of the cylinder.

By forming the admission and exhaust ports in the manner illustrated in the drawings I am able to make said ports large 130

enough to produce an engine which has great power. In an engine of the puppet valve type it is not practicable to provide the engine with very large ports because 5 large puppet valves warp easily and thus do not seat tightly after the engine has been in use for a short period. Consequently, the quantity of combustible gas that can be admitted to the cylinder of a puppet valve 10 engine is limited by reason of the fact that it is not practicable to make the admission and exhaust ports over a certain size. My engine has not this objectionable feature and is not limited to ports of a certain size 15 because the valve which controls the flow of the gases through said ports will not warp out of shape and it is so designed that it can expand and contract. Furthermore, the valve of my engine always remains in engagement 20 with a water-cooled member, namely, the sides of the cylinder, so that the valve does not become so highly heated as the valves of engines of the type heretofore in general use. And still another desirable 25 feature of said engine which makes it practicable from a commercial standpoint is that the valve B does not have to be fitted accurately to the cylinder so as to provide for expansion and contraction, this being due 30 to the fact that the valve consists of an expansion ring which can expand and contract and thus always remain in intimate engagement with the sides of the cylinder.

While I prefer to form the valve B from 35 a split expansion ring I could, of course, use a sectional ring and employ springs for pressing the sections of the ring tightly against the inside of the cylinder. Furthermore, while I have herein illustrated the 40 preferred form of my invention as consisting of an engine in which the slide valve is carried by a piston which forms the end of the cylinder, I do not wish it to be understood that my broad idea is limited to such 45 a construction for, if desired, the end of the cylinder could be immovable and the valve could be mounted on a member provided with stems or other suitable devices that project through the end of the cylinder so 50 as to be engaged by the valve-operating mechanism.

Having thus described my invention, what I claim as new and desire to secure by Letters Patent is:

55 1. An internal combustion engine whose cylinder is provided with admission and exhaust ports through which the gases enter and escape, a reciprocating expansion valve, separate and distinct from the piston of the 60 engine and arranged inside of the cylinder, for controlling the flow of the gases through said ports, and a carrying member for said valve that forms the top of the compression space of the cylinder.

65 2. An internal combustion engine pro-

vided with admission and exhaust ports formed in the sides of its cylinder, a piston for drawing the gases into the cylinder and compressing the gases, a reciprocating expansion valve arranged inside of said cylinder in sliding engagement with the sides thereof for controlling the flow of the gases through said ports, and a carrying member for said valve that forms the top of the compression space of the cylinder. 75

3. An internal combustion engine provided with a cylinder that has admission and exhaust ports formed in the sides thereof, means for igniting the gases that are drawn into the cylinder and compressed, a 80 ring-shaped expansion valve, separate and distinct from the piston of the engine, and arranged inside of the cylinder in sliding engagement with the inner surface of the side walls of the cylinder for controlling the 85 admission and exhaust of the gases through said ports, and an actuating member for said valve that forms the top of the compression space of the cylinder.

4. An internal combustion engine having 90 admission and exhaust ports formed in the sides of its cylinder, a reciprocating valve-carrying member, separate and distinct from the piston of the engine and arranged inside of the cylinder, said member forming 95 the top of the compression space of the cylinder, a ring-shaped expansion valve on said member for controlling the flow of the gases through said ports, and means for preventing said valve from moving longitudinally of the cylinder relatively to said valve-carrying member. 100

5. An internal combustion engine having a port formed in its side walls, a ring-shaped expansion valve arranged inside of 105 said cylinder in sliding engagement with the inner face thereof, a reciprocating valve-carrying member for said valve, separate and distinct from the piston of the engine, and a projection on one of said parts 110 which fits in a recess in the other part so as to prevent the valve from moving longitudinally of the valve-carrying member but not interfering with the radial or outward movement of the valve into snug engagement with the sides of the cylinder. 115

6. An internal combustion engine having a cylinder provided with a movable piston that is separate and distinct from the piston proper of the engine and which forms the 120 top of the compression space of the cylinder, an admission port and an exhaust port formed in the sides of said cylinder, a ring-shaped expansion valve arranged inside of the cylinder and carried by said piston head 125 for controlling the flow of the gases through said ports, and means for operating said piston head so as to cause said ports to be closed on the compression and power strokes of the piston. 130

7. An internal combustion engine having segmental-shaped admission and exhaust ports formed in the sides of its cylinder, a piston that forms the end or head of said cylinder, a ring-shaped expansion valve carried by said piston for controlling the flow of the gases through both of said ports, and means for actuating said piston so as to move said valve into and out of operative position with relation to said ports.

8. An internal combustion engine having a cylinder, a piston that forms the top of the compression space of said cylinder, a cross-head connected to said piston head, a shaft provided with cams that coöperate with said piston head and cross-head to reciprocate the piston, and a valve on said piston head arranged inside of the cylinder for controlling the admission and exhaust of the gases.

9. An internal combustion engine having a cylinder provided in its sides with admission and exhaust ports, a reciprocating piston that forms the top of the compression space of said cylinder, a ring-shaped expansion valve on said piston that controls the flow of the gases through said ports, means for moving said piston head in one direction and holding it at rest while the charge is being compressed and fired, and independent means for moving the piston head in the opposite direction so as to permit the burnt gases to escape from the cylinder.

10. An internal combustion engine having a cylinder which is provided in its sides with an admission port and an exhaust port, a piston that forms the top of the compression space of the cylinder, a valve on said piston head that controls the flow of the gases through said ports into and out of the cylinder, a cross-head connected to said piston head, operating cams coöperating with said cross-head and with the piston head for reciprocating it, and yielding means for holding the cross-head in engagement with the cam that coöperates with same.

11. An internal combustion engine having a cylinder which is provided in its sides with segmental-shaped admission and exhaust ports arranged in different horizontal planes, a piston that forms the head or end of said cylinder, a ring-shaped expansion valve arranged inside of the cylinder for controlling the admission and exhaust of the gases through said ports, means on the piston head which holds said valve far enough below the end of the piston head to permit the combustible gases to enter the cylinder, and means for actuating said piston head so as to move said valve into and

out of operative position with relation to said ports.

12. An internal combustion engine having a cylinder which is provided in its sides with segmental-shaped admission and exhaust ports arranged in different horizontal planes, a piston that forms the head or end of said cylinder, a valve arranged inside of the cylinder for controlling the admission and exhaust of the gases through said ports, means on the piston head which holds said valve far enough below the end of the piston head to permit the combustible gases to enter the cylinder, a cross-head connected to said piston head, and a cam shaft extending through said cross head and provided with cams that engage said cross-head and piston head and move the piston head positively in opposite directions.

13. An internal combustion engine provided with a cylinder, a reciprocating valve-carrying member, separate and distinct from the piston of the engine and arranged inside of the cylinder so as to form the top of the compression space, a valve on said member for controlling the admission and exhaust of the gases, and means for moving said valve-carrying member positively in both directions.

14. An internal combustion engine provided with a cylinder, a reciprocating valve-carrying member, separate and distinct from the piston of the engine and arranged inside of the cylinder so as to form the top of the compression space, a valve on said member for controlling the admission and exhaust of the gases, a cam arranged above said valve-carrying member for moving said member in one direction, and a separate and distinct cam also arranged above said member for moving said member in the opposite direction.

15. An internal combustion engine provided with a cylinder which has admission and exhaust ports formed in the sides thereof adjacent one end of the cylinder, a reciprocating valve-carrying member arranged inside of the cylinder, an expansion valve on said member for controlling the admission and exhaust of the gases through said ports, and a rib on one of said parts which fits in a recess in the other parts and thus prevents the valve from moving longitudinally of said valve-carrying member.

In testimony whereof I hereunto affix my signature in the presence of two witnesses, this 12th day of August 1911.

WILLIAM C. CARTER.
